MOLINS LINKING MACHINE CAL. .30

Worthington M. Jones, Hamden, Conn., assignor to the United States of America as represented by the Secretary of the Army

Application June 21, 1955, Serial No. 517,101

4 Claims. (Cl. 86—48)

(Granted under Title 35, U. S. Code (1952), sec. 266)

The invention described herein may be manufactured and used by or for the Government for governmental purposes, without the payment to me of any royalty thereon.

This invention relates to an improvement in the link abutment plates forming a part of the belt of a machine for linking or assembling belts of machine gun ammunition of the so-called "disintegrating" type wherein the casing of each cartridge forms the pivotal interconnection between mating loops of a corresponding pair of belt links. Such a machine is disclosed in Patent 2,335,646, granted November 30, 1943, in the name of John W. Chalmers. This machine consists essentially of an endless belt formed of a series of interpivoted blocks which passes over and about two spaced drums or sprocket wheel assemblies. The outer faces of these blocks are grooved or fluted to form parallel channels, spaced by the distance between consecutive cartridges in the completed belt and disposed transversely to the direction of travel of the belt. As the belt is driven, mechanism operating automatically in timed relation with travel of the belt, separately feeds links and cartridges into the flutes of the upper pass of the belt as it moves over a flat supporting surface or table. The positions are such that each link lies properly positioned in a channel at one end of its plate, with its single loop in one channel interposed between the double loops of the preceding link and its double loops in the next succeeding channel. The mechanism referred to deposits one cartridge in each channel with the nose of its bullet about $\frac{3}{8}$ inch from the contiguous loop of those occupying that channel.

As the block belt progresses it travels past mechanism which engages the heads of the cartridge casings and progressively forces them toward and into the mating loops in each successive channel to thereby pivotally connect the links. Axial movement of each cartridge continues until it is fully seated in the loops, with its reduced neck portion within the forward one of the double loops.

These double loops of each link grip the casing of its cartridge firmly so that a substantial force must be applied axially to the head of the cartridge casing to force it into position. The reaction to this force is taken by abutments or end plates, one secured to each block of the aforesaid endless belt. Each plate is secured to the side surface of a block at the ends on which the links are automatically deposited and has a serrated edge which upstands above the surface of its block and so dimensioned that the bullet and the forward portion of the neck of each cartridge may pass between side walls of a serration while the front loop of the corresponding link is engaged and held as the cartridge is forced into position as an integral part of the ammunition belt.

The present invention relates to an improvement in the aforementioned end plates of which each machine requires a large number.

In the belt link referred to, as fabricated, the forward edge of the forward or first loop, that is, the one which extends about and grips the reduced, bullet-receiving end

2

of the cartridge case, has a small inclination in both the horizontal and vertical planes, with respect to the central axis of the loops. In the prior art machine referred to, the channels formed in the fluted blocks of the belt are at right angles to the direction of belt travel and, of course, at the same angle with respect to the end plates rigidly attached to the ends of the blocks.

As a result the forward edges of the forward loops contacted the serrations over a limited portion only of their peripheries so that the center of reaction between this loop and the end plate, as the cartridge was forced into mating loops of a pair of links, was offset (1) below the common axis of the loops and (2) rearwardly of such axis with respect to the direction of belt travel. This resulted in a couple being applied to the link when axial thrust was applied to the cartridge which tended not only to turn the link out of its channel in both the vertical and horizontal planes, but also tended to deform or turn the forward loop out of axial alignment with its companion loop. As a result of the distortion of the forward loop necessary to force the cartridges into the loops was excessive with consequent frequent breakage of links, cramping and destruction of cartridges, excessive wear on the end plates and frequent stoppages for repairs and loss of production schedules due to the fact that links sometimes passed beyond their normal support point and into the serrations between end plates.

The main objects of the invention are, therefore, to provide an end plate for the block belt of a linking machine of the type described which overcomes the aforesaid drawbacks, which affords the fullest possible peripheral support for the forward edge of the forward loop as it takes the thrust engendered by forcing a cartridge into the loops, which firmly maintains the links against turning or twisting with respect to the end plates reduces the thrust necessary to force the cartridges into position, largely eliminates link breakage, destruction of cartridge cases and which increases to a remarkable degree the production capacity of the machine.

Other objects and advantages will become apparent from a study of the following description in connection with the accompanying drawings.

In these drawings:

Fig. 1 is a fragmentary elevational view illustrating a portion of a linking machine cartridge conveyor and showing the application of an end plate of the invention thereto.

Fig. 2 is a cross section taken along line 2—2 of Fig. 1 and looking in the direction of the arrows,

Fig. 3 is a sectional detail view taken along line 3—3 of Fig. 1,

Fig. 4 is a fragmental plan view of a portion of the linking machine shown in Fig. 1,

Fig. 5 is a side elevation of an end plate of the invention,

Fig. 6 is a sectional detail view taken along line 6—6 of Fig. 5, a portion of a cartridge link being shown nestled within the counter-bore,

Fig. 7 is a cross section of an end plate showing the counter-bored link supporting surface and a cartridge link in broken lines as illustrated in position after assembly, and

Fig. 8 is a fragmentary perspective view of an end plate illustrating the counter-bored link-supporting surface.

Referring in detail to the drawing, numeral 1, Figs. 1 and 2, identifies the frame of that portion of a machine of the type described wherein the assembled ammunition belt B is being drawn off the machine. A shaft 2a is journaled in the frame and has fixed thereon a pair of identical sprockets 2 having toothed peripheries to engage and positively drive a block belt generally identified

at 3. The belt consists of a plurality of pivotally interconnected blocks 4 having grooved outer faces to define a plurality of parallel equally-spaced channels 5 extending transversely of the direction of belt travel and spaced by the distance between successive cartridges in the completed ammunition belt.

Each block 4 is shown as having four channels with half-channels at its ends which, in conjunction with the half-channel of the preceding and following blocks, form a complete channel so that, when the upper pass of the belt is moving over the plane supporting surface 1a, Fig. 2, formed as a portion of the machine frame, a continuous row of equally spaced channels is formed.

The blocks are provided with integrally connected flanges 6 depending from their inner faces at the respective edges thereof and the ends of these flanges are drilled to receive pivot bolts 8 by which contiguous blocks are connected to the respective ends of short links 7 whereby flexibility of the belt is provided and a space between blocks provided to receive teeth 2b of the sprockets 2 by which the belt is positively driven in timed relation with rotation of the sprockets. The mechanisms by which the links and cartridges are deposited in the channels of the upper pass of the block belt and the means for forcing the cartridges in succession axially along the channels to force them into the mating loops of a pair of contiguous links, are not shown as these form no part of the invention and are, moreover, disclosed in the patent previously identified.

Each of the blocks 4 is provided at the side edge toward which the cartridges are moved, with an abutment plate 9, secured to its block as by flat head screws 10 passing through countersunk holes 9a in the plate and into threaded bores in the block. Each plate has an edge upstanding above the outer face of its plate which edge is serrated to define projections 11 having rounded bottoms 12. As will be clear from Figs. 4 and 5, the end plates are so formed that the bullet of a cartridge will pass smoothly between projections 11 while the forward loop of the link will abut the edges thereof. Each plate is so connected with its block that each projection lies in the same vertical transverse plane as a respective ridge 4 of its block.

Referring to Fig. 8 in particular, it will be noted that the area about and between consecutive projections 11 of the end plate 9 is counterbored as at 14 to receive and seat that portion of the forward loop 15 of a link 16 when the cartridge is forced into linking relation therewith. The axis of the counterbore has a downward inclination of about 2° with respect to the axis of the flutes in the block 4 as shown in Fig. 7 and also an inclination of about 5° rearwardly of the axis of the flutes with respect to the direction of belt travel as shown in Fig. 6.

By the construction described in the foregoing paragraph, and as indicated in the figures referred to, the forward edge of the loop of each link is in contact with bottom of the counterbore 14 to the maximum peripheral extent possible, with the result that the axis of the loops of each link is maintained in alignment with the axis of the cartridge as it is thrust into the loops, and no couple is developed tending to turn or distort the loops. As a result, the thrust necessary to force the cartridges into the loops is a minimum and breakage of links, damaging or destruction of cartridges and damage to the machine is practically eliminated.

My invention results in a very great increase in productivity of a linking machine equipped therewith. As an example, with a machine of the type described, but using a belt block with end plates of conventional construction a production rate of about 285,216 linked cartridges per 16-hour day was sustained, with one production day as low as 59,250 cartridges due to stoppages caused by breakage and jamming of links. After the machine was equipped with end plates constructed in accordance with the invention a sustained daily average

7 production of between 370,000 and 400,000 linked cartridges, about 1600 complete belts of 250 cartridges each, was attained per 16-hour day with practically no work test rejections. A conservatively-estimated sustained increase in output of about 35 to 40 percent was therefore obtained.

It will be clear from the foregoing that a machine equipped with my invention attains the objects recited, and effects a material reduction in costs pursuant to the fabrication of cartridges, links, and machine parts, as well as a corresponding reduction in plant equipment, labor costs and overhead. It will be understood that if the links are fed into the machine with the double loop forward in the direction of belt travel, the inclinations 15 of the counterbore axis previously specified, will be reversed.

While a preferred form of the invention has been shown and described, various modifications and substitutions of equivalents will occur to those skilled in the art after a study of the foregoing disclosure. Hence, the disclosures should be taken in an illustrative rather than a limiting sense, and it is the desire and intention to reserve all modifications within the scope of the subjoined claims.

25 I claim and desire to secure by Letters Patent:

1. In a machine for linking machine gun ammunition belts, a plurality of solid blocks pivotally interconnected in end-to-end relation to form an endless block belt, each said block having its outer face transversely fluted to define a plurality of channels uniformly spaced in the direction of belt travel, and an abutment plate secured to and along one side edge of said block and having an edge projecting outwardly of the outer face of the block, said edge being serrated to pass with a smooth fit the bullet and 30 the forward portion of the neck only of a cartridge resting in a respective channel, said edge being provided in its confronting face with a plurality of counterbores contiguous said serrations, each said counterbore inclining both in a horizontal and a vertical plane with respect to the axes of said serrations.

2. A unit for the loading belt of a machine for linking machine gun ammunition belts, said unit comprising a block having one face fluted to define a plurality of equally-spaced parallel channels extending from side to side of said block, and an abutment plate secured to and coextensive with, one side of said block, said plate having a serrated edge upstanding above the fluted face of said block, the space between serrations being constructed and arranged to pass the bullet and the forward portion of the neck only of a cartridge resting in a corresponding one of said channels, said serrated upstanding edge being provided in its confronting face with a plurality of counterbores contiguous said serrations, each said counterbore inclining rearwardly and downwardly with respect to a horizontal and a vertical plane determined by the axes of said serrations and the confronting face of said edge respectively, and being adapted to receive in line contact, the similarly inclined forward edge of the forward loop of an ammunition belt link when said link rests within a corresponding channel.

3. A unit for the loading block belt of a machine for linking machine gun ammunition belts of the disintegrating type, said unit comprising, a block adapted to form a section of said block belt and having one face fluted to define equally-spaced parallel channels opening through side edges thereof, each channel being adapted to receive the mating loops of consecutive links and a cartridge, and an abutment plate secured to one side edge of said plate and coextensive therewith, said plate having a serrated edge extending outwardly of the fluted surface of said block to define a plurality of notches each aligned with a respective channel, each notch being adapted to pass the bullet and the forward portion of the neck only of a cartridge in the corresponding channel, there being counterbores in the confronting face of said plate each in sub-

stantial correspondence with a respective channel, each said counterbore having an axis inclined at a small angle from the plane determined by the axes of said channels and also at a small angle in said plane, whereby the forward similarly inclined edge of the forward loop of a link resting in the respective channel, has line contact with the bottom of said counterbore.

4. A unit for the loading block belt of a machine for linking machine gun ammunition belts of the disintegrating type, said unit comprising, a rectangular block adapted to form a section of said block belt and having one face fluted to define a plurality of parallel, equally-spaced channels opening through the side edges thereof and having coplanar axes, each channel being adapted to receive the mating loops of a pair of consecutive ammunition belt links and a cartridge, in alignment axially of the channel, and an abutment plate integrally connected to and coextensive with one side edge of said block, said plate having a serrated edge outstanding beyond the fluted surface of

said block to define notches each aligned with a respective channel, each notch being dimensioned to pass the bullet and the forward portion of the neck only of a cartridge in the corresponding channel, there being counterbores in the confronting face of said plate each in substantial alignment with a respective channel, the axis of each counterbore being inclined downwardly by about 2° from the common plane of the axes of said channels and by about 5° rearwardly in said plane with respect to the direction 10 of belt block travel.
